(57) **CLAIM**

The ornamental design for a nose pad for eyeglasses, as shown and described.

DESCRIPTION

FIG. 1 is a front view of a nose pad for eyeglasses of the present invention;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a perspective view thereof;

FIG. 8 is a sectional view thereof taken along the line 8-8 in FIG. 1; and,

FIG. 9 is a right side view thereof with the pad part opened. The broken lines shown in the figures depict portions of the nose pad for eyeglasses that form no part of the claimed design. The alternate long and short dash lines are for the purposes of disclosing boundary lines that form no part of the claimed design.

1 Claim, 9 Drawing Sheets
